(57) CLAIM

The ornamental design for luggage, substantially as shown and described.

DESCRIPTION

FIG. 1 shows a top, front, left side perspective view of the Design, where the pocket is in a closed configuration.

FIG. 2 shows a front view of the Design, where the pocket is in a closed configuration.

FIG. 3 shows a rear view of the Design.

FIG. 4 shows a left side view of the Design, where the pocket is in a closed configuration.

FIG. 5 shows a right side view of the Design, where the pocket is in a closed configuration.

FIG. 6 shows a top view of the Design, where the pocket is in a closed configuration.

FIG. 7 shows a bottom view of the Design, where the pocket is in a closed configuration.

FIG. 8 shows a top, rear perspective view of the Design.

FIG. 9 shows a top, rear perspective view of the Design, where the handle is in an open configuration.

FIG. 10 shows a close-up top, rear perspective view of the Design.

FIG. 11 shows a top, rear, right side perspective view of the Design, where the handle is in an open configuration.

FIG. 12 shows a top, rear, right side perspective view of the Design.

FIG. 13 shows a top, front, left side perspective view of the Design, where the pocket is in an open configuration.

FIG. 14 shows a top, front perspective view of the Design, where the pocket is in an open configuration; and,

FIG. 15 shows a front view of the Design, where the pocket is in an open configuration.

Any broken lines shown in the drawings represent unclaimed portions of the luggage and form no part of the claimed design.

1 Claim, 15 Drawing Sheets
